UNITED STATES PATENT OFFICE.

RUSSELL F. REED, OF SAN FRANCISCO, CALIFORNIA.

MATRIX CLEANER.

Specification of Letters Patent. Patented Aug. 8, 1922.

1,425,132.

Application filed October 7, 1919. Serial No. 329,097.

To all whom it may concern:

Be it known that I, RUSSELL F. REED, a citizen of the United States, residing at the city and county of San Francisco and State of California, have invented new and useful Improvements in Matrix Cleaners, of which the following is a specification.

This invention relates to a linotype machine and particularly pertains to a matrix cleaner therefor. In the operation of linotype machines, it is considered imperative that the exposed faces of the matrices are maintained in a clean condition so that the operator can readily observe the character thereupon. It is common practice to clean a complete font of matrices every few days and this operation usually requires from two to three hours.

It is the principal object of the present invention to provide a simple and effective means by which the matrices may be individually cleaned and burnished during use without requiring any special attention or cleaning operation.

The present invention contemplates the use of a cleaning and burnishing member of plastic material mounted upon the duplex rail of an assembly elevator and disposed in the path of travel of the outer faces of the matrices, thus insuring that each matrix will be burnished and cleaned as it is moved to its proper position in the line.

The invention is illustrated by way of example in the accompanying drawings, in which—

Fig. 1 is a view in perspective, illustrating the invention as particularly disclosing the buffing member.

Fig. 2 is a view in perspective, showing the invention and particularly illustrating the formation of the frame.

Fig. 3 is a view in perspective, showing a matrix.

Fig. 4 is a view in vertical section and elevation, showing the operation of the invention.

Fig. 5 is a view in elevation, showing the position of the present invention upon the duplex rail of an assembly elevator.

Fig. 6 is a view in perspective, illustrating the frame.

In the drawings, 10 indicates a matrix cleaner which embodies the subject matter of the present invention and which is mounted upon the duplex rail 11 of an assembly elevator 12. This elevator is under-

stood to be a part of the assembling mechanism of a linotype machine.

As clearly shown in Fig. 5, the present invention is mounted upon the upper face 60 of the rail 11 and near the long finger 12. In Fig. 4 it will be seen that a set screw 13 is mounted in the front vertical face of the rail 11 and is adapted to enter a slot 14 formed in a lower extension portion of a 65 cleaner frame 15. This frame has a vertical portion lying parallel to rail 15 and side fingers 16 and 17 which act as parallel guides for a block of cleaning and buffing material 18. The side fingers 16 and 17 are 70 formed with guide ribs 19 which enter longitudinal end slots in the buffing block 18 and prevent vertical displacement of this block. The buffing block is substantially rectangular in shape and is preferably formed of 75 rubber, one of the ingredients of which is sand or other gritty material. It has been found in practice that the ordinary ink eraser rubber is most admirably adapted for this purpose. 80

In vertical section the block is substantially rectangular, having a downwardly projecting lip 20 extending between the back face of the rail 11 and a row of matrices 21, which move along the rail 11 and 85 beneath an em scale 22. The buffing block 18 is horizontally adjustable and may be moved outwardly into the path of travel of the matrices by means of adjusting screws 23 which extend through threaded openings 90 in the longitudinal back plate of the frame 15. These screws bear against a pressure plate 24 which rests against the back face of the buffing block and is formed with grooves through which the ribs 19 of the 95 frame may extend.

In operation of the present invention the device is applied as particularly shown in Figs. 4 and 5, after which the buffing block may be adjusted by the screws 23 and these 100 in turn set by lock nuts 26. As the assembling mechanism operates, the matrices will be delivered at the right-hand side thereof and moved along the assembly rail in the direction of arrow a, as indicated in Fig. 5. 105 During this movement the face 27 of the matrices will be brought into frictional engagement with the flat vertical face of the buffing block, which will remove the grease therefrom and burnish the surface so that 110 the inscription thereon may be easily read. It will be evident that due to the peculiar

motion imparted to the matrices a side motion will be given as the matrices move along the buffering block and thereafter a vertical motion given to the matrices, which 5 movement will insure that the face 27 will be cleaned and burnished.

- It will thus be seen that the present invention provides very simple means whereby the matrices of a linotype machine may be automatically cleaned as used, thus eliminating a considerable waste of time in cleaning the font of type at given intervals. It will further be observed that due to the peculiar, resiliency, gritty and non-absorbent character of 10 the buffering member, the surfaces of the matrix rubbed thereover will be thoroughly cleaned and buffed without damaging the matrix by the use of cleaning fluids or without interfering with the operation of the 15 mechanism, including the swinging of the gate.

While I have shown the preferred form of my invention, various changes in the construction and arrangement of the several 20 parts herein shown and described may be resorted to without departing from the spirit of my invention as disclosed in the appended claims.

Having thus described my invention, what 25 I claim and desire to secure by Letters Patent is—

1. A matrix cleaner comprising a frame having a back plate and parallel side fingers, guide ribs formed along said fingers, a buffering block of plastic material adapted to engage said guide ribs and to be seated between

the frame fingers, a pressure plate disposed at the rear of said block, and adjusting members carried by the frame and acting against the pressure plate to adjust the buffer block 40 in relation to the frame.

2. In combination with the assembling mechanism of a linotype machine, a matrix cleaner consisting of a frame secured to the assembly rail, and having buffering block composed of elastic gritty material fitted and guided in said frame, a pressure plate at the rear of the block, and means to adjust the block within the frame. 45

3. A matrix cleaner and burnisher comprising a U-shaped frame member adapted to be secured to a linotype machine, a buffering block of plastic and gritty material slidably mounted in said frame and means for adjusting the buffering block in relation to the frame. 50

4. A matrix cleaner and burnisher comprising a U-shaped frame member adapted to be secured to a linotype machine, a pressure plate slidably mounted in said frame, a buffering block of plastic and gritty material 60 also slidably mounted in the said frame and means for applying pressure to the pressure block so as to adjust the same and the buffering block in relation to the frame.

In testimony whereof I have hereunto set 65 my hand in the presence of two subscribing witnesses.

RUSSELL F. REED.
